UNITED STATES PATENT OFFICE

2,509,097

BARN CLEANER

Elmer E. Hinz, Zumbrota, Minn.

Application June 11, 1948; Serial No. 32,385

3 Claims. (Cl. 198—218)

1

This invention relates to barn cleaners and is designed to automatically remove waste therefrom and retain the barn or stable in sanitary condition.

A primary object of the invention is to provide means for elevating the removed waste to be discharged at a point of disposal and by reverse movement, return the cleaning means to stationary position within the barn.

Another object of the invention is to provide guide means for the conveyor chains as they travel to and from the disposal end of the device; a further object of the invention is to guide the cleaning chains as they travel up an incline so that they will not slip as they leave the barn, thereby displacing the removed waste and rendering the cleaning operation ineffectual and unsanitary.

And a further object of the invention is to mount the cleaner operating assemblies for ready connection with the chain cleaning means, when the desired process is to be carried out.

Other objects of the invention reside in the details of construction and in the combination of the various parts and in their mode of operation, as will hereinafter appear.

The following is a detailed description of a preferred embodiment of the invention and is illustrated in the accompanying drawings, wherein:

Figure 1 is a side elevation of the invention in position with barn chain cleaners;

Figure 2 is a top plan view of the device shown in Figure 1;

Figure 3 is a rear elevation of the invention;

Figure 4 is a side elevation of the invention, and is taken on the opposite side illustrated in Figure 1;

Figure 5 is a diagrammatic view of the invention;

Figure 6 is a transverse vertical section and is taken substantially on the line 6—6 of Figure 1;

Figure 7 is a vertical transverse section and is taken substantially on line 7—7 of Figure 1; and,

Figure 8 is an enlarged detail of the clutch means for actuating the device.

Referring to the figures, the barn cleaner is illustrated generally by numeral 10 and is shown connected to a conveyor chain 12 lying within a gutter 14 of a barn 16. Conveyor chains 12 are placed one on each side of the gutter and are joined transversely by angulated cleaning bars 18. Bars 18 scoop up the deposited manure or other body waste and retain such waste until they reach a point of disposal, as will presently appear. Chains 12 are secured on the interior end thereof to a suitable winding cable 20, cable 20 traveling around idler rollers 22 and 24, rollers 22 and 24 being secured by suitable brackets 26 to the rear wall 28 of barn 16. The front wall 30 of barn 16 is suitably bored at 32 to receive

2

cable 20 therethrough, while the bottom 34 of wall 30 is open and at such height to readily permit conveyor chains 12 to emerge therethrough. As may be readily seen in Figures 1 and 7, as chains 12 emerge through barn 16, they are engaged by idler star wheel 36, wheel 36 including fingers 38 adapted to engage chain 12 by means of forked extremities 40. Star wheel 36 is mounted on transverse shaft 42 and secured at the point of entrance of barn 16, in any suitable manner. Thus, as chains 12 emerge from the barn, force elements 40 engage the links of chain 12, and thereby retain them adjacent the gutter 14 prior to traveling up conveyor 44 and the cleaning assembly 10. The structure described above is conventional and it is believed that further description thereof will not be necessary.

Conveyor trough 44 is inclined upwardly and rearwardly, the front end thereof terminating within the inclined end 46 of channel 14 and the floor 48 of barn 16. Conveyor trough 44 is retained in any suitable manner between support standards 50, standards 50 being mounted on support blocks 52 to be retained in suitable recesses adjacent barn 16. Any suitable means for moving barn cleaner 10 may be provided, since such means forms no part of the instant invention. Of course, when desired, the device may be permanently secured in position.

Support platform 54 is adapted to retain thereon drive motor 56, while a second platform 58 secures thereon cable winding drum 60 to which cable 20 is secured for movement thereon as will soon be explained. Horizontal braces 62 are secured to standard 50 and to trough 44 as may be seen in Figure 1 and mount thereon as by suitable trunnions 64 a chain drum 66.

Chains 12 are adapted to travel on inclined trough 44, upon suitable action of motor 56 in a manner soon to appear, so that the removed barn wastes are carried upwardly on angle bars 18 until they reach the opposite end of trough 44, below which a suitable receiving truck or container is positioned. The waste drops over the free end of trough 44 and conveyor chains 12 are carried over chain drive sprockets 68 secured to trough 44 to be finally wound up on drum 66. Chains 12 thus pass beneath guide bar 70 secured as by rods 72 below conveyor 44. Idler sprocket wheels 74 and 76 are secured to each end of guide bar 70 and are the means over which sprocket chains 12 travel. Thus, tension of chains 12 are maintained at all times, as is desired.

Drive means 56 is connected to pulley wheel 78 by means of a pulley belt 80 trained thereover. Drive shaft 82 extends transversely across standard 50 and projects from each side thereof. Drive sprocket 84 is secured to one end of shaft 82 and is connected as by drive sprocket chain 86 to a

large drive sprocket wheel 88. Wheel 88 is mounted for rotation on shaft 93 and shaft 90 is secured on each end thereof to a large, driven sprocket wheel 92 and a smaller driven sprocket wheel 94. Wheel 92 is connected to sprocket 96 mounted on cable drum 60 for actuation thereof, while sprocket wheel 94 is secured to a friction clutch sprocket wheel 98 for actuation of drum 66. Suitable sprocket chains 100 and 102, respectively, provide the drive means.

Dog clutch 104 is mounted on driven shaft 106, shaft 106 being secured to conveyor trough 44. Clutch lever 108 is mounted on bracket 110 secured to conveyor trough 44 for pivotal movement as at 112 whereby clutch 104 is slid into engagement by suitable key connections 114 with friction sprocket wheels 98. When this is done, shaft 106 rotates a driven sprocket wheel 116 mounted at the opposite extremity thereof, sprocket wheel 116 actuating a second sprocket wheel 118. Sprocket wheel 118 is mounted for rotation on shaft 120 and is operated by sprocket chain 122 trained thereover. This, in turn, rotates pulleys 124 mounted on shaft 126 carrying drum 66 as by crossed pulley belt 128.

Cable drum sprocket wheel 96, mounted on the opposite end of shaft 82, is connected by a second dog ear clutch 130 actuated by clutch handle 132 pivoted at pivot 134 of bracket 136 to rotate sprocket wheel 96 connected by shaft 138 to cable winding drum 60.

In the operation of the device, while clutch 104 is engaged, clutch 130 will be disengaged, and vice versa. Also, it is obvious that when chain 12 is winding up on drum 66, such movements will unwind cables 20 from drum 60, and, in reverse, when drum 60 is winding cable 20, such action will unwind conveyor chains 12. In use, barn cleaning apparatus 10 is connected to cable 20 and chains 12. Motor 56 is started to drive pulley 78 which, in turn, drives sprocket wheel 84 secured on shaft 82. Sprocket wheel 84 drives sprocket wheel 88, which in turn rotates cable drum sprocket 92 and chain drum sprocket 94 in idling position. Chain clutch handle 108 is pivoted to engage clutch 104 with friction sprocket wheel 98. This, in turn, actuates wheel 116 which transmits power to sprocket wheel 120 which, in turn, rotates drum 66. This wheel 120 which, in turn, rotates drum 66. This operation winds chain 12 on the drum, thereby unwinding rotating cable 20. As the cleaning bars 18 leave barn 16, they are prevented from rising and thereby dropping the removed manure or the like, by engagement with star wheel 36. They then travel upwardly over inclined conveyor trough 44 until they have reached the open rear extremity thereof. The wastes are then deposited on a suitable receiving container stationed below, and chains 12 continue their travel to be wound on drum 66. In this travel, they are guided by guide bars 70 and over idler sprocket wheels 74 and 76, whereby suitable tension is always maintained on cleaning chains 12. Idlers 74 and 76 are adjustable, not shown, to vary the tension, as is needed. When reverse operation is desired, clutch 104 is disengaged and clutch 130 is engaged with sprocket 92. This causes power to be transmitted to sprocket wheel 92, which in turn rotates wheel 96 for winding of cable drum 60. Such movement causes the now freely rotating chain drum 66 to unwind chains 12 which are returned to their original positions within the barn. Chains 12 and cable 20 are then disengaged, and the device moved to another barn, if mounted on portable means, or

is then retained in position until necessary to be used again.

Any suitable material that is desired may be used in the construction of the invention, and while one complete embodiment has been described in detail, it is to be understood that various features of the invention may be independently used and also that numerous modifications might be made by those skilled in the art, without departure from the spirit and scope of the invention, as indicated above, and in the following claims.

Having described the invention, what is claimed as new is:

1. In a barn cleaner, a supporting frame, an inclined trough carried by said frame, a cable winding drum disposed above said trough and a chain winding drum disposed below said trough so that the vertical medial planes of said drums and trough coincide, a drive shaft journaled on said frame, power means for rotating said shaft, means including a clutch drivingly connecting the drive shaft to the cable winding drum, and means including a second clutch drivingly connecting the drive shaft to the chain winding drum, a pair of chain sprockets rotatably mounted below the trough at the upper end thereof and a pair of star wheels rotatably mounted above the trough at the lower end thereof, said clutches being operable to selectively rotate either of said drums, guide means disposed below said trough and between said sprockets and chain winding drum for guiding cleaner chains including laterally spaced and inclined bars depending from said trough for supporting cleaner chains.

2. The combination of claim 1 including idler rollers secured to said bars for tensioning cleaner chains.

3. In a barn cleaner, a frame including a pair of vertical support standards, an inclined trough disposed between said standards and being secured intermediate its ends to the standards for support, a cable winding drum disposed above said trough and a chain winding drum disposed below said trough so that the vertical medial planes of said drums and trough coincide, said chain winding drum being disposed between said standards and the lower end of said trough, a drive shaft journaled on said frame, power means for rotating said shaft, means including a clutch drivingly connecting the drive shaft to the cable winding drum and means including a second clutch drivingly connecting the drive shaft to the chain winding drum, a pair of chain sprockets rotatably mounted below the trough at the upper end thereof and a pair of star wheels rotatably mounted above the trough at the lower end thereof, and a pair of laterally spaced, inclined guide bars depending from the trough between the standards and the upper end of the trough for supporting cleaner chains.
